UNITED STATES PATENT OFFICE

2,242,836

PROCESS OF PRODUCING AROMATIC
HYDROCARBONS FROM OLEFINSAlexander S. Ramage, Detroit, Mich., assignor to
Coals and Chemicals, Limited, Los Angeles,
Calif., a corporation of Nevada

Application June 7, 1937, Serial No. 146,895

2 Claims. (Cl. 260—449)

This invention relates to a process of production aromatic hydrocarbons from petroleum oils, and more particularly to conversion of the paraffinic hydrocarbons of petroleum to olefinic compounds, and then converting the olefinic compounds, as well as any olefins originally present in the petroleum, into hydrocarbons of the aromatic series.

One of the objects of the invention is to increase materially the proportion of compounds of the aromatic series recovered from petroleum. A further object is to provide such a process which will produce a gaseous product suitable for use, with a minimum of treatment, as an illuminating gas for use by the general public, such gas having a high heating value and a rate of flame propagation below the maximum rate set as permissible for such use. Still further objects are to provide such a process which can be economically carried out, which utilizes simple apparatus, and which can be readily controlled.

In U. S. Letters Patent No. 1,224,787, issued to me May 1, 1917, there is described a process of transforming mineral oils to convert the paraffin components into olefins components, to convert the olefins into terpenes, and to convert the terpenes into aromatic hydrocarbons, by passing the oils in the vapor state over a reducible oxide, the temperature being between 580° C. and 750° C. (1076° F. to 1382° F.) if the oxide used is ferric oxide.

In general, the present invention comprises carrying out such process to convert the paraffinic hydrocarbons predominantly to olefins, and then passing such olefinic gases and vapors, mixed with carbon monoxide and a small quantity of steam, through a second converter, in the tubes of which they are contacted with finely divided iron, at a pressure approximately equal to atmospheric pressure, and at a temperature between 1100° F. and 1300° F., to convert such olefinic hydrocarbons to hydrocarbons of the aromatic series and low boiling alcohols, particularly methanol.

The accompanying drawing is a diagrammatic representation of the essential parts of an apparatus for carrying out the process, showing the direction of flow of the various gases, vapors and liquids, by which the hydrocarbons, predominantly olefins, produced from paraffinic hydrocarbons by the method and apparatus described and shown in my U. S. Patent No. 1,224,787, are converted into hydrocarbons of the aromatic series and low boiling alcohols, particularly methanol.

As described in said U. S. Letters Patent No. 55

1,224,787, the oil, after the asphaltic content has been removed in any suitable manner, is vaporized in a pipe still to approximately 800° F. and passed through an expander into a converter. The vapors, consisting largely of compounds of the paraffin series up to approximately hexadecane, that is, having up to sixteen carbon atoms, are passed at a temperature of approximately 800° F. into a converter in which they are contacted with a reducible oxide, preferably ferric oxide, to convert such paraffins into the corresponding olefin compounds. As described in such patent the ferric oxide is maintained at a temperature between about 1075° F. and 1375° F., being regulated in accordance with the boiling point of the hydrocarbon to be converted. For example, an oxide temperature range between 1075° F. and 1150° F. is preferably used for conversion of paraffinic hydrocarbons having boiling points between 300° F. and 400° F. The oxide is heated electrically, or otherwise, in such a way that its temperature may be readily and accurately controlled, and it has been found that, with suitable increase or decrease of the oxide temperature to suit the increasing boiling point of the predominating hydrocarbon passing through the converter, a reaction product is obtained which is substantially free of hydrocarbons of the paraffin series, and which consists predominantly of hydrocarbons of the olefin series. In carrying out the present invention the steps outlined above are carried out in accordance with the teaching of U. S. 1,224,787, to convert the paraffinic hydrocarbons predominantly to olefins. 30 Such resultant vapors of hydrocarbons of the olefin series are further treated by the apparatus indicated, and in the manner indicated, in the drawing forming a part of this application, by being mixed with steam, the steam being in amount equal to about 10% to 15% of the vapors, and with a volume of carbon monoxide approximately equal to the combined volume of vapors and steam, and the mixture is passed through a second converter in which it is intimately contacted with finely divided iron particles, preferably spongy iron or iron in the form of iron turnings, or wool, and heated to a temperature between 1100° F. and 1300° F. It has been found that a temperature of approximately 1200° F. is preferable, and the pressure can be only slightly above atmospheric pressure. It will be understood that the pressure is varied to regulate the rate of passage of the mixed vapors through the converter. With tubes three inches in diameter and thirty feet long a rate of flow such as results

from vaporizing ten gallons of oil per tube per hour has been found to be preferable. While the reaction will occur at atmospheric pressure, higher pressures can be used in practice in order to utilize a converter of smaller construction. In the converter the olefinic hydrocarbons, upon contact with the iron particles, are converted into hydrocarbons of the aromatic series and the low boiling alcohols, particularly methanol, and the resulting gases contain from 30% to 40% of olefinic gases together with methane and excess of carbon monoxide (CO).

It is believed that the conversion of the olefinic hydrocarbons to aromatic compounds is due to the decomposition of the steam by the iron to form nascent hydrogen and ferrous oxide (FeO), and their reaction with the hydrocarbon compounds to form compounds having successively less hydrogen content, together with nascent hydrogen which forms formaldehyde and methanol with the carbon monoxide, as indicated in the following in which nascent hydrogen is indicated as H_2 :

Thus the CO is hydrogenated to CH_3OH (methanol) by the nascent hydrogen and the $\text{C}_n\text{H}_{2n+2}$ (paraffins) are dehydrogenated to $\text{C}_n\text{H}_{2n-6}$ (aromatics).

In each instance it will be noted that it is assumed that the iron again decomposes the water to form FeO and nascent hydrogen and that the effect under the conditions stated is to convert the hydrocarbon compound to one having two less hydrogen atoms and to convert the CO to CH_2O (formaldehyde) which is similarly converted to CH_3OH (methanol).

The vapors from the second converter are purified and condensed in the usual manner to provide a high yield of benzol, toluol, xylol mixture which may be used as a basis for high-compression motor fuel, or for any similar purpose.

The uncondensed gas constitutes an excellent basis for the production of illuminating gas, particularly since, because of its low hydrogen content, its rate of flame propagation is low, while its B. t. u. value is relatively high.

The treatment of the hydrocarbons in the second converter in accordance with the present invention differs from the process described in U. S. Letters Patent No. 1,812,372, issued to me

June 30, 1931, mainly in that in the method of the present application no hydrogen is mixed with the carbon monoxide and the olefin hydrocarbons treated are not only those having five or less carbon atoms but vapor mixtures containing olefins of still greater molecular weight such as those which may be formed in the first converter from paraffin vapors containing undecane and dodecane in considerable quantities and up to and including hexadecane and heptadecane, that is, formed from paraffins having boiling points up to 500° F. to 600° F., provided that the amount of steam is increased up to 30% of steam, in accordance with an increase in the number of carbon atoms in the predominating hydrocarbons present. The reaction by which the hydrocarbon compounds are converted successively to others relatively poorer in hydrogen is believed to be due to the reaction of the hydrocarbon and the ferrous oxide producing metallic iron and nascent hydrogen which nascent hydrogen combines instantly with the CO and, as stated above, the gaseous product resulting from the present process is substantially free of hydrogen, whereas that of the process described in such patent contained a large proportion of uncombined hydrogen and had a rate of flame propagation so high as to prevent its use as a substitute for illuminating gas of low flame propagation, such as natural gas.

What I claim is:

1. The process of converting hydrocarbons of the olefinic series into hydrocarbons of the aromatic series and low-boiling-point alcohols which comprises successive dehydrogenation of said olefinic hydrocarbons in the vapor phase by reacting them, at substantially atmospheric pressure and at a temperature of about 1100° F. to about 1300° F., with steam in an amount equal to about 10% up to 30% of that of such olefinic vapors and with carbon monoxide in an amount approximately equal to the combined amounts of such vapors and steam in the presence of finely divided iron.

2. The process of converting hydrocarbons of the olefinic series containing up to sixteen carbon atoms into hydrocarbons of the aromatic series and low-boiling-point alcohols which comprises mixing said hydrocarbons in vapor form at substantially atmospheric pressure and at a temperature of about 1100° F. to about 1300° F. with steam in an amount equal to about 10% up to 30% of that of the olefinic vapors and with carbon monoxide in an amount approximately equal to the combined amounts of the vapors and steam, in the presence of finely divided iron, formaldehyde and methanol being formed as successively hydrogenated products of the carbon monoxide by the reaction of nascent hydrogen, and the olefinic hydrocarbon compounds being successively dehydrogenated.

ALEXANDER S. RAMAGE
